UNITED STATES PATENT OFFICE.

GEORGE N. KNOTT AND PERCY W. KNOTT, OF PHILADELPHIA, PENNSYLVANIA.

LAUNDRY-IDENTIFYING MEANS.

Application filed December 29, 1921. Serial No. 525,816.

To all whom it may concern:

Be it known that we, GEORGE N. KNOTT and PERCY W. KNOTT, citizens of the United States, residing at Philadelphia, in the 5 county of Philadelphia and State of Pennsylvania, have invented certain new and useful Improvements in Laundry-Identifying Means, of which the following is a specification.

10 The herein described device relates to laundry identifying means of such nature and construction as to make it adaptable for use in large or small plants with no extra equipment, and using no greater floor 15 space than maintained and no special construction of rooms, bins or shelves.

One of the objects of the invention is to provide a simple and practical device which can be easily, quickly and efficiently used 20 by anyone for the purpose specified.

A further object is to provide an article that is easily manufactured and at a small cost, as well as simple in construction, being pliable, compact and having no complicated parts to become broken as well as lost. It will be found to be sanitary as the article 25 can readily be cleaned at any time. Easily shipped or transported from one location to another.

30 While the foregoing explains the general purpose and objects of the device, other objects and advantages will be found in the specifications that follow, in which the novel features, construction and arrangement of 35 the several parts will be brought out described and claimed.

In the accompanying drawings, forming 40 a part of this specification, and in which corresponding parts are denoted by like designating numerals is illustrated the preferred form of the embodiments of the invention capable of carrying the same into practical operation, it being understood that the invention is not necessarily limited 45 thereto, as various changes in shape, size and proportions of the several parts may be resorted to without departing from the principle of the invention or sacrificing any of its advantages, in which:—

50 Figure 1 is a plan of the pliable tag.

Figure 2 is a plan of the removably attached tag.

Figure 3 is a plan of another method of attaching the removably attached tag.

55 To more fully describe the drawings, and to make clear the operation and the purpose

of the herein described device:—The numeral 1 shows a pliable canvas tag, or like material, shaped to be wider at one end than the other maintaining at its broadest 60 width a series of spaced openings 4 which can be either secured by eyelets or sewed on the edges to prevent unravelling, the pliable tag also maintains an opening 2 by which the device can be hung if necessary or desired; other openings 3 are provided in order to afford additional uses as shown by 4. A small tag 6 to which is secured a removably attached securing means 5 is provided, which in the present consists of a pronged gripping member which can be sprung open in order to removably 65 secure the same in one of the openings 4. It can be understood that the method as shown by 5' can readily be used, that is by 70 slipping a piece of twine through 6' in the small tag and 4 in the pliable member 1 and then slipping it over the small tag. On the pliable member 1 and the smaller tag which 75 can be constructed of such material as to give efficient service, there can be placed certain identifying means such as numerals, names or any like designating means.

When a wash has been received from a customer, a tag bearing a designating means 85 is assigned to that particular customer. The contents are separated, silk stockings being placed in a mesh bag and a small tag 6 detached from the pliable member 1 and attached to the mesh bag. Colored articles; 90 white goods; laces and small rugs are treated in like manner, each lot receiving a small tag. When the wash has been finished, the bags are gathered and after the wash has been properly gathered together the small 95 tags are attached to the pliable member. By this method there is no danger of the goods of one customer being placed with that of another.

Having thus described our invention, what 100 we claim as new, and desire to secure by Letters Patent, is:—

1. In a device for the purpose set forth, in combination an impervious and pliable member of greater length than breadth at 105 its broadest portion, and tapering therefrom, indicating means maintained thereon, the broadest portion maintaining a plurality of apertures and supplemental engaging members maintaining like indicating means. 110

2. In a device for the purpose specified, in combination an impervious and pliable

member with one extremity of a relatively greater width than the opposite end and of greater length than the width at its broadest portion, a series of spaced means for removably attaching a plurality of identifying means and supplemental members adapted to be removably attached and maintaining like identifying means.

In testimony whereof we affix our signatures in the presence of two witnesses.

GEORGE N. KNOTT.
PERCY W. KNOTT.
